DESIGN FOR A GAME BOARD

Herman C. Guetschoff, Detroit, Mich.

Application December 17, 1934, Serial No. 54,453

Term of patent 3½ years

To all whom it may concern:

Be it known that I, Herman C. Guetschoff, a citizen of the United States, residing at Detroit, in the county of Wayne and State of Michigan, have invented a new, original, and ornamental Design for a Game Board, of which the following is a specification, reference being made to the accompanying drawing, forming part thereof.

I claim:

The ornamental design for a game board as shown.

HERMAN C. GUETSCHOFF.
